[57] CLAIM

The ornamental design for an animal trap, as shown and described.

DESCRIPTION

FIG. 1 is a perspective view of an animal trap showing my new design;

FIG. 2 is a rear view of the animal trap of FIG. 1;

FIG. 3 is a front elevational view of the animal trap of FIG. 1;

FIG. 4 is a top view of the animal trap of FIG. 1;

FIG. 5 is an elevational view from the left side of FIG. 1, the right elevational view being a mirror image thereof; and

FIG. 6 is a front elevational view of the animal trap of FIG. 1 with the door in an opened condition.

FIG. 1

FIG. 2

FIG. 3

FIG. 4

FIG. 5

FIG. 6
